FLUID CATCH ROTARY JAR

James Allen Kammerdiner, Los Angeles, Calif.

Application October 29, 1932, Serial No. 640,140

6 Claims. (Cl. 255—27)

This invention relates to a jar for producing an impact blow in a string of pipe, tubing, rods, or the like, wherein a longitudinal stress is exerted upon the string. A specific application of the invention is its use in loosening tools, "fishing" in well holes for lost parts, tools, or equipment called "fish" which have become lodged or "frozen" in the hole. In such instances, a grip is obtained upon the fish by means of a suitable fishing tool disposed at the end of a string and jarring is resorted to in order to dislodge the fish. The string of pipe used in well drilling for tools has elasticity, such that if the jar is placed at the bottom of the string, an upward pull exerted and the jar tripped, an impact of great magnitude is obtained. There are other conditions in which a downward drive is desirable, such as in splitting pipe, perforating casings, and vibrating casing to determine frozen locations. In such instances, the jar may be tripped by an accumulation of the load on the drill string, the position of the catch elements being reversed in relation to that wherein a pull on the string is exerted for jarring.

The primary object of the present invention is to provide a jar, the impact parts of which are held in set position by a fluid catch, and which may be tripped by sustaining a longitudinal stress upon the jar. A more specific object of this invention is to provide a jar of the character described which is held in set position by the resistance of the movement of a plunger or the like snugly fitting in a cylinder or barrel, the jar being released by withdrawing the plunger from its barrel. The plunger is restrained to an initial slow movement creating a partial vacuum in the barrel which is broken on the plunger riding out of its barrel and being suddenly released, thus tripping the jar.

These objects together with other objects and corresponding accomplishments are obtained by means of the embodiment of my invention illustrated in the accompanying drawing, in which:—

Fig. 1 is an axial section through a jar in set position; Figs. 2, 3, and 4 are sections as seen on the lines correspondingly numbered in Fig. 1; and Fig. 5 is a fragmentary sectional view on an enlarged scale of a modified form of the jar.

Referring more particularly to Fig. 1, the jar comprises two sections, a bowl A and a mandrel B telescopically related and having a catch indicated by C to hold the sections in set position.

The bowl includes a tubular shell 6 threaded to receive a head 7 provided with a tapered threaded pin adapted to be received in the sock-

et of a tool joint forming a part of a drill string. The other end of shell 6 is threaded to receive a hammer nut 8 having a square bore. Head 7 has a stuffing box 9 to accommodate a wash pipe on the mandrel. Extending into the head 7 are plunger barrels 10 having ports 11 communicating with the exterior of the head. The ports are controlled by ball checks 12 permitting free egress of fluid from the barrels and preventing ingress. Bleeder ducts 13 are provided in head 7 permitting slow entrance of fluid to the barrels. Slidably mounted within the shell 6 is the mandrel having a head 14 forming an anvil for coaction with hammer 8. The head 14 has longitudinal recesses 15 to allow play of liquid in the shell above and below the head and thus prevent impedance to reciprocation. A square stem 16 extends from the head and through the bore of nut 8, there being recesses 17 to ease the movement of the mandrel. Extending through the mandrel is a bore 18 internally threaded at the upper end to receive a wash pipe 19 serving as a continuation of the passage through the mandrel and slidably mounted in the head 7. The lower end of stem 16 is provided with a tapered threaded pin 20 arranged to be connected to a tool joint. Secured to the anvil head 14 are plungers 21 adapted to slide into and out of the barrels 10.

It will be noted that the jar sections are held against rotation in relation to one another so that the drill string of which the jar forms a part may be used to rotate any tool attached to the lower end. The jar sections may have a limited longitudinal movement being arrested at one end by engagement of the hammer 8 with anvil 14 and limited at the other end by engagement of anvil 14 with head 7. In the latter position, plungers 21 will be disposed within barrels 10. Entrance of the plungers into the barrels is comparatively free, any trapped liquid passing out of the barrels through bleeder ducts 13 and ports 11, valves 12 opening to permit egress. However, withdrawal of the plungers is checked by the closure of valves 12 and fluid can only bleed slowly into the barrels through ducts 13. The jar is placed in a string of tubing, the pipe 19 and passage 17 permitting circulation to be maintained through the string. The jar is set by lowering the drill string and thereby moving the anvil head 14 toward head 7 so that plungers 21 fully enter the plunger barrels 10. This contracts or sets the jar, the plungers being trapped and yieldably holding the jar sections in contracted position. A grip having been obtained on the fish, a pull is exerted upon the drill string. This tends to cause the jar to ex-

5 and. The plungers 21 tend to move out of their respective barrels, but due to the smallness of ducts 13 and the tightness of the fits of the plungers in their barrels, a partial vacuum will be created and fluid can only enter the barrels slowly, thereby checking withdrawal and tripping of the jar. Fluid bleeding into the plunger chambers through the leak ducts permits slow movement of the hammer 8 toward the anvil 14. Elasticity of 10 the drill string permits the latter to stretch and store energy for an impact blow. When the plungers override the lower ends of the plunger barrels, the mandrel is released and the hammer 8 strikes the anvil 14 with an impact of such violence that it either dislodges or aids in dislodging the fish.

15 In Fig. 5, the parts shown for the bowl are the same as in Fig. 1 except that leak or bleeder ducts 13 in head 7 are omitted. The like parts are correspondingly numbered. To replace ducts 13, the plungers 21 are provided with longitudinally extending ducts 22 opening at the outer ends of the plungers and at the roots opening laterally by way of side branches 23. The head 7 is dished 20 slightly so that branches 23 are open to the liquid within the bowl when the plungers are fully inserted. The operation is obvious, ducts 22 enabling liquid to bleed into the plunger barrels.

25 What I claim is:—

30 1. In a rotary jar, a barrel member comprising an elongated hollow shell of substantial internal diameter, a mandrel member projecting into said shell and mounted for reciprocating movement within said shell, said two members having cooperating impact faces which abut against each other in response to, and limit, outward movement of said mandrel member from said barrel member, one of said members defining a suction cylinder closed at one end and merging at the 35 other end into the space within said shell, the other of said members comprising a piston aligned with and fitted to said suction cylinder and so dimensioned and positioned longitudinally that it penetrates said suction cylinder when said members are in closed position and leaves the suction cylinder during opening movement prior to contact of said impact faces, the cross sectional area of the space within said shell being at least several times as great as the cross sectional area of 40 said suction cylinder, whereby resistance to opening movement of said members resulting from fluid friction about said piston is negligible after said piston leaves said suction chamber.

45 2. In a rotary jar, a barrel member comprising an elongated hollow shell of substantial internal diameter, a mandrel member projecting into said shell and mounted for reciprocating movement within said shell, said two members having cooperating impact faces which abut against each other and limit outward movement of said mandrel member from said barrel member, one of said members defining a plurality of suction cylinders positioned alongside each other, said cylinders each being closed at one end and merging 50 at the other end into the space within said shell, the other of said members comprising a plurality of pistons aligned with and fitted to said respective suction cylinders and so dimensioned and positioned longitudinally that they penetrate said suction cylinders when said members are in closed 55 position and leave the suction cylinders during opening movement prior to contact of said impact faces.

60 3. In a rotary jar, a barrel member comprising an elongated hollow shell of substantial in-

ternal diameter, a mandrel member projecting into said shell and mounted for reciprocating movement within said shell, said two members having cooperating impact faces which abut against each other and limit outward movement of said mandrel member from said barrel member, one of said members defining a plurality of suction cylinders positioned alongside each other, said cylinders each being closed at one end and merging at the other end into the space within 10 said shell, the other of said members comprising a plurality of pistons aligned with and fitted to said respective suction cylinders and so dimensioned and positioned longitudinally that they penetrate said suction cylinders when said members are in closed position and leave the suction cylinders during opening movement prior to contact of said impact faces, the total cross sectional area of the pistons being less than the cross sectional area of the space surrounding said 15 pistons within said shell when said pistons are retracted from said suction cylinders.

20 4. In a rotary jar, a barrel member comprising an elongated hollow shell of substantial internal diameter closed at the upper end by a 25 longitudinally thick end wall, the latter containing and defining a suction cylinder, the inner end of which opens into the interior of said shell, the opposite end of said shell having a 30 flange extending radially inwardly, the inner end of which flange constitutes an impact face, a mandrel member extending into said shell through the flanged end thereof, having a shaft portion slidably engaging said flange and guided by the inner wall of said shell, the outer side of 35 said head portion constituting an impact face adapted to contact said impact face on said flange when the mandrel member is in outermost position with respect to said barrel member, said head having at its inner end a projecting piston 40 aligned with and dimensioned to seal in said suction cylinder, whereby it enters the cylinder when the mandrel member is in innermost position with respect to the barrel member, the depth of entry of said piston into said cylinder being substantially less than the total relative travel 45 between said members.

50 5. In a rotary jar, a barrel member comprising an elongated hollow shell of substantial internal diameter closed at one end by a longitudinally thick end wall, the latter containing and defining a plurality of suction cylinders, the inner ends of which open into the interior of said shell, the opposite end of said shell having a 55 flange extending radially inwardly, the inner annular face of said flange constituting an impact face, a mandrel member extending in said shell through the flanged end thereof, having a shaft portion slidably engaging said flange and guided thereby and a head portion of larger 60 dimensions slidably engaging and guided by the inner wall of said shell, the outer, annular face of said head portion constituting an impact face adapted to contact said impact face of said flange when the mandrel member is in outermost position with respect to said barrel member, said head having on its upper end a plurality of projecting pistons aligned with and dimensioned to seal in said respective suction cylinders, whereby they enter the cylinders when the mandrel member is in innermost position with respect to the barrel member, the depth of entry of said 65 pistons into said cylinders being substantially less than the total relative travel between said members.

6. A rotary jar as defined in claim 5 in which said mandrel member has a fluid passage extending therethrough with a pipe axially positioned on the inner end of said mandrel member, said pipe connecting with said passage in said mandrel member and extending through a packing joint provided therefor in said thick end wall of said barrel member, and said cylinders and pistons being symmetrically positioned about the longitudinal axis of said members.

JAMES ALLEN KAMMERDINER.
